Primary Examiner — Kathleen L Jones*Assistant Examiner* — Jasmine L. Comedy(74) *Attorney, Agent, or Firm* — Merchant & Gould P.C.(57) **CLAIM**

The ornamental design for a temporary restroom, as shown and described.

DESCRIPTION

FIG. 1 is a front isometric view of a temporary restroom according to the present disclosure;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a cross-sectional front view of the temporary restroom taken along the line 8-8 in FIG. 4, showing an interior of the temporary restroom.

The broken lines in the Figures depict portions of the temporary restroom that form no part of the claimed design.

1 Claim, 8 Drawing Sheets(56)
